(Cl. D58—5)

Fig. 1

Fig. 2

FIG. 1 is a perspective view of a jug embodying my new design.

FIG. 2 is a side elevation view thereof. The opposite side of the jug is like that shown in FIG. 2 and the side of the jug opposite the handle is plain.

The side not shown is a mirror image of the side shown in FIG. 2. The side opposite the handle is substantially plain.

I claim:

The ornamental design of a jug, substantially as shown and described.
